U.S. Appl. No. 29/552,142, filed Jan. 20, 2016, S. Uratani.
U.S. Appl. No. 29/552,146, filed Jan. 20, 2016, S. Uratani.*Primary Examiner* — Barbara Fox*Assistant Examiner* — Mary C Ramirez(74) *Attorney, Agent, or Firm* — Fitzpatrick, Cella, Harper & Scinto(57) **CLAIM**

The ornamental design for a cartridge, as shown and described.

DESCRIPTION

FIG. 1 is a front view of a cartridge showing our new design; FIG. 2 is a rear view thereof; FIG. 3 is a top plan view thereof; FIG. 4 is a bottom plan view thereof; FIG. 5 is a left side view thereof; FIG. 6 is a right side view thereof; FIG. 7 is a front, top perspective view thereof; and, FIG. 8 is a rear, bottom perspective view thereof. The broken lines shown in the drawings illustrate portions of the cartridge that form no part of the claimed design.
